UNITED STATES PATENT OFFICE.

THOMAS ALLEN DAVIS, OF MEDORA, NORTH DAKOTA.

TRAIN-ORDER HOLDER.

1,305,994.

Specification of Letters Patent. Patented June 10, 1919.

Application filed January 22, 1919. Serial No. 272,466.

To all whom it may concern:

Be it known that I, THOMAS A. DAVIS, a citizen of the United States, and a resident of Medora, in the county of Billings and 5 State of North Dakota, have invented certain new and useful Improvements in Train-Order Holders, of which the following is a specification.

My invention is an improvement in train order holders, and has for its object to provide a device of the character specified for holding the hoops by means of which train orders and the like are delivered to moving trains, in such manner that the hoops may 10 be easily caught by a trainman, either in the cab of the locomotive or in the caboose, without danger to the employees, and wherein the necessity of any one to hold the hoop on the platform is dispensed with.

20 In the drawings:

Figure 1 is a front view of the improved holder and its support;

Fig. 2 is a similar view of the holder, with parts in section;

25 Fig. 3 is a perspective view of one of the blocks;

Fig. 4 is a section on the line 4—4 of Fig. 1;

Fig. 5 is a perspective view of one of the 30 jaws;

Fig. 6 is a perspective view of a portion of the support showing the mounting for the holder.

In the present embodiment of the invention an arm 1 is provided, which is pivoted to a semaphore post 2, by means of a cross head 3 on one end of the arm, which is journaled in bearings 4 on the semaphore post. This arm carries at its opposite end 35 a cross head 5, which extends vertically with respect to the arm, as does also the cross head 3, and it will be noted that the cross head 5 is spaced apart from the adjacent end of the arm.

40 45 Blocks 6 of suitable material, as, for instance, hard wood, are connected to the cross head above and below the arm, by means of clips 7, a clip being arranged near each end of each block. A holder is connected 50 with each block for the hoops 8 of ordinary construction, the said hoops being already in use, and each having a radial arm 9 by means of which it may be conveniently handled.

55 In use, the operator or other employee stands upon the platform with a hoop, hold-

ing the hoop by the handle, the hoop carrying the message, as, for instance, a train order, to be delivered. The trainman, as, for instance, the engineer or conductor, runs 60 his arm through the hoop as it is held by the operator, and there is always more or less danger of injury to the operator or other employee who holds the hoop. In delivering orders in this manner the operator must stand close to the train, a post of considerable danger, especially with freight trains, which may have pieces of boards or lumber projecting from the cars, and the suction of the train has a tendency 65 to swing the hoop, to cause the trainman to miss running the arm through the hoop. With the present invention, the hoops are held by the holders above mentioned, which engage the handles 9. Each of these holders 70 consists of a pair of jaws 10 and 11 each jaw 11 being pivoted in a mortise in the adjacent block, near the end of the block remote from the arm 1, and the jaw 10 also engages within the mortise which holds the 75 jaw 11.

The jaw 10 is rigidly secured to the block, while the jaw 11 is pivoted to the block, in order that it may swing away from the jaw 10 into the dotted line position of Fig. 1. 80 These jaws are recessed longitudinally on their abutting faces, as shown, to receive the handle 9 of the hoop, the movable jaw being normally spring pressed toward the fixed jaw by means of a coil spring 12 which 85 is connected at one end to the arm 1 and at the other to a stirrup 13 which embraces the adjacent pair of jaws and is connected to the movable jaw, the fixed jaw passing through the stirrup.

90 In the present embodiment of the invention two holders are shown for holding the hoops, one in position to be engaged by the arm of a trainman on the engine and the other for engagement by the arm of a trainman on the caboose. It is obvious that one holder might be used or that by extending the cross head 5 other holders might be added. The cross head 3 and each block 6 is prevented from downward movement by 95 means of angle brackets 14. These angle brackets are secured to the cross head or to the post 2, as the case may be.

100 In operation, to insert the hoop it is only necessary to move the jaw slightly away 110 from the fixed jaw, after which the handle may be inserted, or if the recesses for the

handle are beveled or flared at their outer ends the handle can be inserted merely by pushing it into place. Once in place, it is firmly held in a fixed position, so that the 5 trainman will have no trouble thrusting his arm through the hoop.

The jaws will release the handle as soon as pressure is brought to bear upon the hoop.

I claim:

- 10 1. A device of the character specified comprising a hinged support mounted to swing in a substantially horizontal plane into and out of operative position, said arm carrying a substantially vertical cross head near its outer end, a pair of jaws connected with each end of the cross head, the innermost members of the pairs being fixed, and the outermost members being hinged to swing toward and from the fixed members, a stirrup connected with the outer member of
- 20

each pair and through which the inner member passes, and a spring connecting each stirrup to the arm.

2. A device of the character specified comprising a cross head, a pair of jaws connected with each end of the cross head, the innermost members of the pairs being fixed and the outermost members being hinged to swing toward and from the fixed members, and a yielding connection between the outermost members for drawing them toward the innermost members, said connection comprising a stirrup connected with the outer member of each pair and encircling the inner member, and a spring connecting the 30 stirrups.

THOMAS ALLEN DAVIS.
